United States Patent Office.

A. E. ROBERTS, OF DES MOINES, IOWA.

Letters Patent No. 79,145, dated June 23, 1868.

IMPROVED SCHOOL-SEAT AND DESK.

The Schedule referred to in these Letters Patent and making part of the same.

TO ALL WHOM IT MAY CONCERN:

Be it known that I, A. E. ROBERTS, of Des Moines, in the county of Polk, and in the State of Iowa, have invented certain new and useful Improvements in Combined Seats and Folding Desks; and do hereby declare that the following is a full, clear, and exact description thereof, reference being had to the accompanying drawings, and to the letters of reference marked thereon.

In the annexed drawings, forming part of this specification—

Figure 1, is a side view, with the desk in position for use.

Figure 2, a side sectional view, with the desk folded.

Figure 3, a side view of the desk alone; and

Figure 4 a plan view.

The nature of my invention consists in a seat and desk combined, so arranged that the lid, which serves for the top of the desk, can be folded forward from the scholar, so as to make ample room for the pupil to pass to and fro between the desk and the seat; also, in providing the seat with a box on top for books, and the desk-lid with a slate-surface on top, and a portfolio underneath.

To enable others skilled in the art to make and use my invention, I will proceed to describe its construction and operation.

In the annexed drawings, P represents a frame, of cast iron, with legs, which are fastened to the floor, and which frame serves as a support for the seat A, and for the desk-lid E. A represents the seat for two scholars, with a box, B, standing upright in its centre, between them, for books. C is the back of the seat, which extends up as high as the top of the frame P. On top of the frame P and the back C of the seat runs a strip of wood, D, provided with hole a, for inkstand, and grooves b b, for pencils, &c., as shown in fig. 4. The desk-lid E, made of wood, is provided with a slate-surface, G, on top, and with a portfolio, F, underneath, for the use of the pupils; and it slides down in grooves H, on the inside of the frame, when it is not in use. Behind these grooves H, on the frame P, are pivots K, which run into grooves on the slats I, which are fastened on the desk-lid, and serve to support the lid steadily when folding back, and also when before the pupil, ready for use. The slats I are provided with notches r, which, in connection with a flange, n, on the inside of the frame P, and just underneath the strip D, serve to make a close joint between the strip and the lid when it is ready for use. The lid then rests on the top marked M of the frame P.

When the desk is in the position shown in fig. 1, and it is desired to fold it, raise the lid E, when the pivots K, running in the grooves on the slats I, will guide it into the grooves H in the sides of the frame P; and in like manner when it is desired to open the desk for use, raise the lid E out of the grooves H; the pivots K will guide it so that the flanges n will fit into the notches r on the slat I, and the lid will make a close joint with the strip D resting on the top, M, of the frame P.

Having thus fully described my invention, what I claim as new, and desire to secure by Letters Patent, is— The arrangement of the slate-surfaced folding lid E, with its notched and grooved slats I, in combination with the grooved frame P, its flanges n, stationary seat A, and book-holding partition B, the several parts being constructed and used substantially as and for the purposes set forth.

In testimony that I claim the foregoing, I have hereunto set my hand, this 30th day of April, 1868.
